UNITED STATES PATENT OFFICE.

WILLIAM A. G. WILSON, OF BRIDGEPORT, CONNECTICUT, ASSIGNOR TO THE ARTISTIC BRONZE CO., OF BRIDGEPORT, CONNECTICUT, A CORPORATION OF CONNECTICUT.

DESIGN FOR AN ICE-CREAM-CONE HOLDER.

46,195.

Specification for Design.

Patented July 28, 1914.

Application filed May 27, 1914. Serial No. 841,392. Term of patent 3½ years.

To all whom it may concern:

Be it known that I, WILLIAM A. G. WILSON, a citizen of the United States, residing at the city of Bridgeport, in the county of Fairfield and State of Connecticut, have invented a new, original, and ornamental Design for an Ice-Cream-Cone Holder, of which the following is a specification, reference being had to the accompanying drawing, forming part thereof.

The figure is a perspective view of an ice cream cone holder, showing my new design.

I claim:

The ornamental design for an ice cream cone holder, as shown.

WILLIAM A. G. WILSON.
